ROBERT LEWIS JOHNSON, OF EAST ORANGE, NEW JERSEY.

DESIGN FOR A DISH.

Design No. 19,423, dated November 12, 1889.

UNITED STATES PATENT OFFICE.

ROBERT LEWIS JOHNSON, OF EAST ORANGE, NEW JERSEY.

DESIGN FOR A DISH.

SPECIFICATION forming part of Design No. 19,423, dated November 12, 1889.

Application filed September 14, 1889. Serial No. 323,961. Term of patent 7 years.

To all whom it may concern:

Be it known that I, ROBERT LEWIS JOHNSON, of East Orange, in the county of Essex and State of New Jersey, have invented and produced a new and original Design for Dishes, of which the following is a specification.

The leading feature of my design consists of the peculiar shape and ornamentation shown in the accompanying photograph, to which reference is made. Said outline exhibits a curve *a* merging into a line of beauty *b*, and an opposite curve *c* merging into a line of beauty *d*. The similar curves are not op-

posite each other, but are offset, forming the diagonally-opposite points *e f*. A curved line *g* makes in from these points *e f*, as clearly shown in the annexed photograph, and the handle *h* is diagonally arranged coincident with the points *e f* and lines *g*, as shown. 15 20

I claim—

The design for table-ware herein described, and illustrated in the accompanying photograph.

ROBERT LEWIS JOHNSON.
